CLAIM

The ornamental design for a tire, as shown and described.

DESCRIPTION

FIG. 1 is a perspective view of a tire showing our new design, it being understood that the tread is repeated throughout the circumference of the tire, it being understood that the sidewall forms no part of the claimed design;

FIG. 2 is a front elevation view thereof;

FIG. 3 is a rear elevation view thereof;

FIG. 4 is a side elevation view thereof, as seen from the right of FIG. 2; and

FIG. 5 is a side elevation view thereof, as seen from the left of FIG. 2.

FIG. 6 is a perspective view of a tire, it being understood that the tread is repeated throughout the circumference of the tire;

FIG. 7 is a front elevation view of said tire;

FIG. 8 is a rear elevation view of said tire;

FIG. 9 is a side elevation view of said tire, as seen from the right of FIG. 7;

FIG. 10 is a side elevation view of said tire, as seen from the left of FIG. 7;

FIG. 11 is a detail view of the tire of FIG. 7; and,

FIG. 12 is a partial section view of said tire taken along plane SP shown in FIG. 11 that shows just the sectioned portions along plane SP.
